UNITED STATES PATENT OFFICE

2,638,705

ORNAMENTAL BIRD HAVING ROTATABLE WINGS

Albert W. Petras, Stratford, Conn.

Application October 7, 1949, Serial No. 120,017

1 Claim. (Cl. 46—53)

1

This invention relates to toys having wind-operated moving parts, such as wind-driven rotary sails, wings or the like, and particularly to inexpensive toys of this type such as are frequently sold by hawkers at fairs, street celebrations and similar places.

In order to conserve space and permit carrying as large a number as possible, toys of this type are usually packed with the parts disassembled. Salesmen assemble the parts to form complete toys as rapidly as they are sold. When business is brisk, it is important that this operation be accomplished quickly and easily to facilitate sales, and an object of this invention is to provide a novel, appealing, wind-operated toy the parts of which are so constructed and arranged as to contribute to both reducing the cost of manufacture and increasing the ease of assembly.

In one specific aspect, the invention can be employed to simulate a bird in flight and it is so described herein for disclosure purposes. However, it will be apparent that the different features constituting the invention are equally adapted to other forms of toys employing wind-driven rotary members.

A feature of the invention is the formation of wind responsive members from relatively flat, flexible strips which may be a plastic or the like having spaced slits adjacent one end which adapt it to be easily and quickly mounted on flat supporting arms. The latter are so formed as to automatically impart to the flat strips the requisite angle and direction to render them operable by the wind.

A further feature is the use of inexpensive eyelets which can be cheaply produced on a screw machine, for mounting and supporting in a relatively thin body member, which may be of cardboard, or other suitable material, a rotary shaft on which the wind-operated wings are secured.

Other features and advantages will herein-after appear.

In the accompanying drawings:

Figure 1 is a side elevation of a toy constructed in accordance with one embodiment of this invention.

Fig. 2 is a front elevation looking from the right of Fig. 1, and

Fig. 3 is a sectional view through the rotary supporting shaft for the rotating wind driven members.

As illustrated herein for the purposes of disclosure, the invention is shown as a toy intended to simulate a bird in flight. In this embodiment

5 it comprises a relatively thin body member 5, which may be cardboard or other suitable material, cut or stamped to provide a silhouette simulating a bird in flight. The body member is shown mounted on a supporting standard 6 in the form of a small diameter rod having a slotted end 7 in which the lower edge of the body portion 5 is frictionally held. The body portion can be provided with any color combination desired and the front end is shown as shaped and colored to provide a beak 8, eye 9, etc.

10 The wing action of a bird in flight is simulated by rotary wind-driven members 11 resembling a bird's wings and formed of thin flexible material which may be of a suitable plastic. The inner end portion of each wing member has spaced slits 12, 13 for mounting on a flat sheet metal supporting arm 14. A square opening 16 is punched in each arm 14 near one end. The 15 punching forms prongs 17 on the sides of each opening which penetrate the surface of a wooden supporting shaft 18 on which the arms are mounted. The shaft extends rotatably through an unclinched eyelet 19 which is supported by a press fit in a clinched-over eyelet 21 riveted to the body portion 5.

20 The unclinched eyelet 19 forms a hollow bearing sleeve for the shaft 18 and is firmly held in place by the press fit. The eyelet head 22 at one end and the end face 23 at the other form thrust 25 bearings against which the sheet metal arms 14 supporting the wing members 11 abut and thus properly center the shaft 18, as well as properly position the arms 14 relative to the body member 5. As illustrated, each rotary member 11 is

30 shaped to simulate a bird wing. Each supporting metal strip 14 is bent at such an angle as to hold each wing member 11 at the proper angle relative to the body portion 5 so that when the toy is held with the flat side of the body member 5 toward the wind, the wing members 11 will be caused to rotate and, in rotating, to simulate the wing action of a bird in flight. As illustrated, suitable decorative feathers 24 are provided at the head and tail.

35 It will be apparent that the body member 5, the supporting stick 6 and the wing members 11 can be packed and shipped separately and can be easily and quickly assembled by a salesman or other individual without difficulty, merely being necessary to fix the wing members 11 on the supporting arms 14 by slipping the latter through the slits 12 and 13 as shown in Fig. 1. This automatically imparts the desired angle to the wing members for operation by the wind. The body

member can then be easily mounted in the slotted end of the supporting rod 6 and the toy is complete.

It will be apparent that the invention can be variously modified and adapted and that portions of the improvements can be employed without others.

I claim:

A toy comprising a body member having a profile simulating a bird in flight and having an elongate shaft-receiving bearing member extending transversely thereof with the ends projecting from each side of the body, a rotary shaft extending through said bearing member and projecting outwardly beyond each end thereof, a pair of flat sheet metal arms, each having a shaft-receiving opening therein provided with prongs on the outer side of each arm to bite into said shaft to rotate therewith and hold the arms on said shaft and against the ends of said bearing member and the shaft against longitudinal displacement in said bearing member, and a pair of wind-actuated wings having a profile simulating the wings of a bird in flight, said wings

being provided with a pair of spaced transversely extending slits to receive the flat arms and secure the wings thereto and against rotation thereon, said wings rotating said shaft by wind pressure.

ALBERT W. PETRASY.
